LIQUID DISPENSER

Howard Charles Allen, Vancouver, British Co-
lumbia, Canada

Application April 20, 1936, Serial No. 75,311

12 Claims. (Cl. 225—1)

My invention relates to improvements in liquid dispensers which are particularly adapted for use in serving beer and other carbonated foaming drinks. The objects of the invention are to provide a machine capable of filling drinking glasses as fast as the average operator can handle them; to provide means whereby refrigeration of the dispenser is unnecessary even during slack periods when the draw off is taken at lengthy intervals, by draining the liquid back to the barrel in the cold room; to provide means for complete washing out of the dispenser when desired, and to provide automatic means for maintaining a predetermined gas pressure upon the liquid in the dispenser when not discharging.

The invention consists essentially of a reserve tank, a measuring vessel, means for maintaining a predetermined pressure in the tank and the measuring vessel, and means for transferring liquid from the tank to the vessel and from the vessel to discharge, as will be more fully described in the following specification and shown in the accompanying drawings, in which:

Fig. 1 is a sectional view taken half on the line 1—1 and half on the line 1—1A of Figure 2.

Fig. 2 is a transverse sectional view taken on the line 2—2 of Figure 1.

Fig. 3 is a transverse sectional view taken on the line 3—3 of Figure 1.

Fig. 4 is a detail view of the operating lever stop mechanism.

In the drawings like characters of reference indicate corresponding parts in each figure.

For the purpose of clarity certain parts have been omitted from some of the figures.

The numeral 1 indicates a casing having front and rear walls respectively numbered 2 and 3, and side walls 4 and 5. In the upper part of the casing a feed tank 6 is formed, which is provided with a top closure 7 and a bottom wall 8. Below the feed tank, measuring devices 9 are provided, which are coupled together for alternate operation by a rock shaft 10 from a lever 11 which is conveniently disposed to one side of the casing 1. The measuring devices 9 are identical in general construction, but oppositely arranged as to disposition of their elements.

The measuring devices 9 consist of chambers 12 and 12A, having top closures 13 and 13A and bottom closures 14 and 14A. A transfer pipe 15 leads from the bottom wall 8 of the feed tank 6 to ported passages 16 and 16A formed in the bottom closure. Spring closed inlet valves 17 and 17A are interposed between the passages 16 and 16A and the chambers 12 and 12A respectively.

Stand pipes 18 and 18A extend downwards from above the maximum liquid level of the feed tank 6 to ports 19 and 19A and spring closed foam valves 20 and 20A are coupled with the valves 17 and 17A and are interposed between the chambers 12 and 12A and ports 19 and 19A. The valves 17 and 20 and the valves 17A and 20A are alternately opened by forks 21 and 21A mounted upon the rock shaft 10. Spring closed discharge valves 22 and 22A communicate between the chambers 12 and 12A respectively and a ported passage 23 which leads to a discharge spout 24. Spring closed relief valves 25 and 25A communicate between the chambers 12 and 12A and the atmosphere and are adapted to be thrust open by the valves 22 and 22A respectively almost immediately after these latter valves have been raised to open by fingers 26 and 26A extending from the rock shaft 10.

The feed tank 6 is supplied with beer, under suitable CO₂ pressure from below, through a feed pipe 30 which extends to a point above the maximum liquid level in said tank and is provided at its free end with a float valve 31 which closes when a predetermined level is reached. A branch 32 leads from the feed pipe through a valve 33 to the bottom of the tank, the purpose of which will hereinafter be described.

Gas pressure is provided for the interior of the feed tank from a CO₂ pipe 34, see Figure 3, which branches out from a T 35 to a pipe 36 leading into the feed tank and provided with a normally open valve 37 which is opened by a float 38 when a minimum reserve of liquid has entered the tank through the pipe 30, the gas passing through the float valve 37 to a pressure control valve generally indicated by the numeral 39.

The pressure control valve 39 is provided with a standard 40 supporting a cylinder 41 through which a stem 42 extends. The stem is fitted at its base with a valve closure 43 and at its upper end with a button 44 abutting a flexible diaphragm 45. The stem 42 is urged upwardly by a spring 46 of suitable tension, so that when the pressure within the tank is below normal, while a normal liquid reserve is in the tank, the spring 46 will urge the diaphragm upwards and lift the closure valve 43 off its seat to allow the gas pressure in the tank to be raised. Obviously when the pressure is raised to normal, the pressure on the upper surface of the diaphragm will be great enough to close the valve 43.

Extending from the opposite end of the T 35 and preferably formed integrally therewith, is a valve 47 from which a branch pipe 48 extends

through the bottom wall 8 to a point adjacent the top closure 7 of the tank 6.

A stand pipe 49 extends downwardly through the tank 6 from above the maximum liquid level and is fitted at its lower end with a blow off or safety valve 50. This safety valve is only relied upon to function under abnormally high pressure within the system and forms no essential part of the invention. Extending downwardly through the tank and into the casing 1 is an air relief pipe 51 which is fitted with a valve 52 which is closed by a float 53 when the minimum liquid reserve is in the tank the valve is therefore normally closed. At the base of the pipe 51 is a normally open valve 54 having a stem 55 which on being raised closes the valve against gas relief from the tank.

Mounted horizontally adjacent the wall 4 is a shaft 56 which extends through one wall of the casing and is fitted with a hand lever 57. Secured upon the shaft within the casing are three cams 58, 59 and 60, which are respectively adapted to engage the stems of the valves 54, 47 and 33 when the lever 57 is rocked.

Pivotedly mounted upon one of the casing walls 25 is a bell crank 61 having a horizontal leg 62 which extends below the stem of the valve 54 and having a vertical leg provided with a slot 63 through which the crank is operatively connected by a pull rod 64 extending through the casing wall so that when the rod is pulled outwardly the valve 54 is closed, thus shutting off the air relief pipe 51 and the interior of the tank 6 from communication with the atmosphere irrespective of the float valve 52.

The operation of filling either of the chambers 12 or 12A is accomplished in the movement of the hand lever 11 from the end of its stroke back to a vertical or normal position, and so that the lever may not be moved say from its extreme right position to normal and then back to right again, I provide a stop mechanism such as is shown in Figure 4 in which 65 indicates a quadrant secured to the shaft 10 having arcuate shoulders 66 and stops 67 and 67A. In the centre of the quadrant a projection 68 is formed having opposed apertures providing a centre lug 69 and side lugs 70 and 70A. Two brackets 71 and 71A are mounted from the casing 1 between which brackets the quadrant 65 is adapted to rock. Each of these brackets slidably supports a plunger 72 and 72A, these two plungers are provided with enlarged outer ends 73 and 73A respectively and knobs 74 at their inner ends which are adapted to be engaged by the lugs of the quadrants. Slidably vertically of the quadrants are keepers 75 and 75A which are provided adjacent their upper ends with key hole slots 76 having their enlarged parts uppermost and of such size as to accommodate the enlarged outer ends 73 and 73A of their respective plungers 72 and 72A, while their narrower portions embrace the intermediate portions of said plungers.

The quadrant as shown in Figure 4 is in normal or centre position indicated by the dotted line C and has been brought there on the last movement of the lever 11 from the position indicated by the dotted line R, therefore the keeper 75A being disengaged by the plunger enlargement 73A has dropped onto the stop 67A and the quadrant and lever are prevented from being moved back to the position R and must necessarily be moved next towards the dotted line position L.

In moving the lever to the L position, the stop

67A raises the keeper 75A so that when the lug 70A engages the plunger 72A and draws its enlargement 73A into the enlarged portion of the key hole slot of the keeper 75A, it retains said keeper in raised position free from the shoulder 66 of the quadrant. The final movement of the quadrant to the L position causes the lug 69 to drive the plunger enlargement 73 out of the enlarged portion of the key hole slot of the keeper 75, thus allowing said keeper to ride on the shoulder 66 and as the lever is returned to C position to drop to the slot 67, thus preventing the lever's return until it has completed its movement to the R position.

In operating the dispenser, assuming the tank 15 6 to be empty, the float valve 37 on the CO₂ branch pipe 36 will be closed and the float valve 31 on the beer feed pipe will be open, and since there will be no gas pressure in the tank the pressure controlled valve 42 will be open. On gas 20 pressure being applied to the beer supply below the machine and the main beer line valve, not shown, being opened, beer will rise through the pipe 30 and the open valve 31 into the tank. Air in the tank will be purged out through the open float valve 52, the pipe 51 and the open valve 54 to atmosphere. When the minimum reserve level is reached in the tank, the float 53 will have risen, closing the valve 52, thus closing the system and allowing the incoming beer 30 to build up a pressure. It should be here pointed out that normally the same gas pressure, when admitted to the tank, will be the same as that supplied to the top of the supply barrel. The beer will flow into the tank until the pressure 35 therein is equal to that in the barrel less the static head of beer between the barrel and the valve 31.

When the liquid level is raised to a predetermined point, the float valve 31 will close, thus 40 shutting off further entry of beer to the tank 6. Assuming that a new keg of wild beer is tapped and that after filling an undue pressure develops from the occluded gas in the beer, the safety valve 50 will open and purge the system of the 45 excess pressure, so that undue foaming will not take place when beer is admitted to either of the measuring chambers 12 and 12A.

Assuming that the hand lever 11 is moved from normal to the L position, the fork 21 will cause 50 the inlet valve 17 and the foam valve 20 to open, so that beer from the tank 6 may flow by gravity through the pipe 15 into the chamber 12 and allow any foam forming during filling to pass through the valve 20 into the pipe 18 where it 55 may condense to flow back later on a subsequent opening of said valve. This will fill the chamber 12 in which the beer will be held on the closing of said valves incidental to the return of the lever to normal or C position. When the lever is 60 moved over in the opposite direction, to the R position, the chamber 12A will be filled in a similar manner to that above described and simultaneously finger 26 will open the valves 22 and 25. It will be noticed that due to the gap between the stems of these two valves, the valve 25 will lag slightly behind the valve 22 in opening, so that the chamber 12 will commence to discharge with the opening of the valve 22 and will continue to discharge by gravity as soon as 70 the valve 25 opens. The movement of the lever 11 from normal position to the end of its stroke will therefore cause one chamber to fill and one to discharge and the return of the lever to normal will close all the valves leading to and from 75

said chambers, so that lever movement in the opposite direction will fill the chamber last discharged and discharge the chamber last filled.

During slack periods, in order that the beer in the tank may not assume room temperature, it is desirable to return it to the source of supply which is kept in a cold room or otherwise chilled. To do this, the lever 57 is rocked, thus rocking the cams 58, 59 and 60 and operating the valves 54 and 47 and 33 in the order named. This valve movement first closes the air relief pipe 51, next admits gas through the pipe 48 to the top of the tank and subsequently, though this may be arranged to take place simultaneously, establishing communication between the beer feed pipe 30, the branch 32 and the bottom of the tank 6. The beer is then permitted to flow downwards through the valve 33, back to the source of supply by gravity since the gas pressure at the tank and the source of supply are now equal. As soon as the lever 57 is returned to normal position, the tank becomes relieved of pressure through the valve 52 and the pressure from below will again cause the beer to enter 25 and fill it to the point determined by the float valve 31.

The system is washed out by forcing water through it from a feed pipe 71 and a wash out pipe 78 and also by operating the lever 11.

Should it be desired for any reason to empty the system without returning the beer in the tank back to the source of supply, the rod 64 is pulled outwardly, thus closing the valve 54, the flow from the source of beer supply would be 35 shut off and the lever 11 manipulated in the usual manner. In this way gas would enter the feed tank to prevent any subatmospheric pressure developing during discharge through the discharge passage 23.

40 What I claim as my invention is:

1. A drink dispenser comprising a sealed tank having an inlet and being adapted to be fed from a source of liquid supply, means for admitting liquid to the tank up to a normal level, a measuring chamber connected to said tank, said chamber having an inlet valve communicating between the chamber and the tank, a foam valve communicating between the chamber and the tank above the normal liquid level and a discharge valve for discharging the liquid from the chamber and a lever for operating the valves of the chamber.

2. A drink dispenser comprising a sealed tank having an inlet and being adapted to be fed from a source of liquid supply, means for admitting liquid to the tank up to a normal level, a measuring chamber connected to said tank, said chamber having an inlet valve communicating between the chamber and the tank, a foam valve communicating between the chamber and the tank above the normal liquid level and a discharge valve for discharging the liquid from the chamber and a lever for operating the valves of the chamber and a relief valve operable in conjunction with the discharge valve for admitting atmospheric air to the chamber when said discharge valve is opened.

3. A drink dispenser comprising a sealed tank having an inlet and being adapted to be fed from a source of liquid supply, means for admitting liquid to the tank up to a normal level, a measuring chamber connected to said tank, said chamber having an inlet valve communicating between the chamber and the tank, a foam valve communicating between the chamber and the tank and the

tank above the normal liquid level and a discharge valve for discharging the liquid from the chamber and a lever for operating the valves of the chamber, said lever being adapted when moved in one direction to open the inlet valve 5 and the foam valve and when moved in the opposite direction to open the discharge valve.

4. A drink dispenser comprising a sealed tank having an inlet and being adapted to be fed from a source of supply, means for admitting liquid to the tank up to a normal level, a measuring chamber connected with the tank, valve means having a unitary operating lever for delivering liquid from the tank to the chamber and for discharging the liquid from the chamber, a pipe communicating between the upper part of the chamber and the tank above the liquid line, and a valve controlling the flow through said pipe, said valve being adapted for operation by said operating lever.

5. A drink dispenser comprising a sealed tank adapted to be filled from a source of supply under gas pressure, a measuring chamber in communication with said tank and a valve mechanism for admitting liquid from the tank to the chamber and for discharging the said liquid therefrom, said tank having a liquid inlet pipe controlled by a float valve, a gas inlet pipe and means for closing off the gas inlet pipe when a predetermined pressure is developed in said tank.

6. A drink dispenser comprising a sealed tank adapted to be filled from a source of supply under gas pressure, a measuring chamber in communication with said tank and a valve mechanism for admitting liquid from the tank to the chamber and for discharging the said liquid therefrom, said tank having a liquid inlet pipe controlled by a float valve, a gas inlet pipe and a float valve to said gas inlet pipe for shutting off the gas pressure until a predetermined quantity of liquid is admitted to the tank.

7. A drink dispenser comprising a normally sealed tank, a measuring chamber connected with the tank, a valve mechanism for admitting liquid from the tank to the chamber for passing air or foam from the chamber to the tank as the chamber fills and for discharging liquid from the chamber, a float valve controlled liquid inlet to the tank to admit liquid under pressure, a gas inlet pipe to the tank, and means for admitting gas through said pipe to maintain a predetermined pressure when the liquid in the tank is within predetermined levels, and means for closing off said pressure and opening the tank to atmospheric pressure when the liquid is below a predetermined level.

8. In a dispenser of liquid normally under pressure and having a feed tank, a measuring chamber below said feed tank, a liquid inlet valve communicating between the tank and the chamber, a relief valve between the tank and the chamber, a discharge valve for withdrawing the liquid from the chamber, and a valve for admitting atmospheric air to the chamber when the discharge valve is open, said discharge valve being arranged to open prior to the opening of the air admitting valve.

9. In a dispenser of liquid normally under pressure and having a feed tank, a measuring chamber below said feed tank, a liquid inlet valve 70 communicating between the tank and the chamber, a relief valve between the tank and the chamber, a discharge valve for withdrawing the liquid from the chamber, and a valve for admitting atmospheric air to the chamber when the

- discharge valve is open, said discharge valve being arranged to open prior to the opening of the air admitting valve, and unitary means for operating all of said valves.
5. 10. In a dispenser of liquid normally under pressure and having a feed tank, a measuring chamber below said feed tank, a liquid inlet valve communicating between the tank and the chamber, a relief valve between the tank and the chamber, a discharge valve for withdrawing the liquid from the chamber, and a valve for admitting atmospheric air to the chamber when the discharge valve is open, said discharge valve being arranged to open prior to the opening of the air admitting valve, a lever adapted to open the valves communicating between the tank and the chamber simultaneously when moved in one direction and to open the discharge and air admitting valves when moved in the opposite direction.
10. 11. In a drink dispenser having two measuring chambers each having an inlet and a discharge valve, a rock shaft operatively connected to the valves of each chamber, said rock shaft having a normal neutral position and being adapted when moved to one side of neutral position to open the inlet to fill one chamber and when moved to the opposite side of the neutral position to open the inlet valve to fill the second chamber and to open the valve to discharge the previously filled chamber, and means preventing the rock shaft to be moved in the same direction from neutral in successive movements.
15. 12. In a drink dispenser having two measuring chambers each having an inlet and a discharge valve, a rock shaft operatively connected to the valves of each chamber, said rock shaft having a normal neutral position and being adapted when moved to one side of neutral position to open the inlet to fill one chamber and when moved to the opposite side of the neutral position to open the inlet valve to fill the second chamber and to open the valve to discharge the previously filled chamber, and means preventing the rock shaft to be moved in the same direction from neutral in successive movements, said means comprising a quadrant secured to the shaft, said quadrant having opposing arcuate shoulders and stops, a support adjacent each end of the quadrant, a pair of keepers carried by the supports adapted to be actuated by the quadrants, one of said keepers being adapted to be raised as the quadrant moves in one direction towards neutral position and the other keeper being adapted to slide along an arcuate shoulder and as the quadrant returns to neutral position to engage the stop and prevent said quadrant from returning over its former movement until it has been moved beyond neutral position and to the limit of its stroke.
20. 25. 30. HOWARD CHARLES ALLEN.
